ELECTRIC SHAVER

Henricus Franciscus Theresia Schellens, Drachten,
Netherlands, assignor to North American Philips
Co., Inc.

Filed June 22, 1967, Ser. No. 7,556

Claims priority, application Switzerland Dec. 30, 1966

Term of patent 14 years

Int. Cl. D28—03

U.S. Cl. D95—3

FIG. 1 is a perspective view of an electric shaver, showing my design;

FIG. 2 is a front elevation;

FIG. 3 is a rear elevation;

FIG. 4 is an elevation of one side;

FIG. 5 is an elevation of the other side;

FIG. 6 is a bottom plan view thereof; and

FIG. 7 is a top plan view thereof.

The characteristic features of my design for an electric shaver reside in the combination of a cutting head and a cylindrical pillar-like handle, the cutting head having a contrastingly textured panel on the front and rear face thereof, two ends extending beyond the circumference of the handle, and a bracket framing the ends and bottom of the cutting head all as shown.

I claim:

The ornamental design for an electric shaver, as shown and described.
